[57] CLAIM

The ornamental design for a holder for bags of milk, as shown and described.

DESCRIPTION

FIG. 1 is a perspective view of a holder for bags of milk showing my new design;

FIG. 2 is a top plan view thereof;

FIG. 3 is a right side elevational view thereof;

FIG. 4 is a front elevational view thereof;

FIG. 5 is a rear elevational view thereof;

FIG. 6 is a bottom plan view thereof;

FIG. 7 is a perspective view thereof;

FIG. 8 is a fragmentary cross-sectional view thereof;

FIG. 9 is a perspective view of an alternative embodiment of FIG. 1; and,

FIG. 10 is a top plan view of FIG. 9.

FIG.1.

FIG. 2.

FIG. 3.

FIG. 4.

FIG. 5.

FIG. 6.

FIG. 7.

FIG. 8.

FIG.9.

FIG.10.
